JEWEL BOX

Lee H. Rankin, Johnstown, Pa.

Application March 8, 1932, Serial No. 597,595

10 Claims. (Cl. 206—1.5)

My invention relates to new and useful improvements in a box or receptacle and more particularly to a box or receptacle in which jewels or similar articles may be placed for safe keeping and only opened for the removal of the articles by a person knowing the required movements or manipulations to release the locking mechanism.

The principal object of the present invention resides in the provision of a box or receptacle of the character described including keyless locking mechanism, the mechanism being released by placing the receptacle or box in different positions and moving certain parts one relative to the other.

Another object of the invention consists in forming the box or receptacle of two parts, one of which is adapted for movement relative to the other and providing means for normally locking the parts against relative movement, the locking means being released by placing the box or receptacle in different successive positions and then moving the parts one relative to the other.

With the above and other objects in view, which will appear as the description proceeds, my invention consists in the novel details of construction and arrangement of parts described in the following specification and illustrated in the accompanying drawing, and while I have illustrated and described the preferred embodiments of the invention, as they now appear to me, it will be understood that such changes may be made as will fall within the scope of the appended claims.

In the drawing:—

Fig. 1 is a top plan.

Fig. 2 is a longitudinal vertical section on the line 2—2 of Fig. 1 looking in the direction of the arrows.

Fig. 3 is a side elevation, in inverted position, showing the initial movement of one section of the box or receptacle relative to the other.

Fig. 4 is a top plan showing the initial relative movement of the sections; and

Fig. 5 is a top plan showing the sections moved into open position.

In the drawing 1 indicates the bottom section and 2 the top section of my improved form of box or receptacle. Secured to and carried by the bottom section 1 are the upwardly extending studs or projections 3 and 4 having the outer ends enlarged to provide the heads 5 for a purpose which will be later apparent. The upper section 2 is provided, at one end, with the relatively short elongated slot or recess 6 and at its opposite end is provided with the relatively long elongated slot or recess 7, these slots or recesses 6 and 7 receiv-

ing the studs or projections 3 and 4 as quite clearly illustrated in the drawing with the heads 5 of said studs or projections overlying the sides of the slots or recesses and the upper face of the top section 2, as shown more particularly in Fig. 1 of the drawing. In the normal positions of the sections 1 and 2 the stud or projection 3 will be received at the inner end of the slot or recess 6 while the stud or projection 4 will be positioned intermediate the ends of the slot or recess 7, as shown more particularly in Fig. 1 of the drawing.

The bottom section 1 is provided in its upper surface, adjacent one end, with the recess 8 and adjacent its opposite end with a recess 9 and intermediate these recesses is provided with an elongated recess 10 which is normally in alignment with a similarly elongated recess 11 formed in the bottom of the top section 2. The top section 2 is also provided in its under surface, adjacent one end of the recess 11, with a recess 12 and adjacent the opposite end of the recess 11 is provided with a recess 13, the recess 12, with the parts in their normal position, being in alignment with the recess 8 in the bottom section while the recess 13 will be out of alignment with the recess 9, as shown more particularly in Fig. 2 of the drawing. As shown the recess 8 is somewhat more shallow than the recess 12 whereas the recess 9 is of greater depth than the recess 13 for a purpose which will be later apparent. A locking pin 14 is normally received within the recess 8 with a portion projecting into the recess 12 and a locking pin 15 is normally received within the recess 9, this pin 15 being of a length corresponding to the depth of the recess 9 but of greater length than the depth of the recess 13.

The parts are normally in the positions shown in Figs. 1 and 2 of the drawing, vertical separation of the sections 1 and 2 being prevented by the heads 5 on the studs or projections 3 and 4, longitudinal movement of the sections one relative to the other being prevented by the locking pin 14, and swinging movement of one section relative to the other being prevented by the studs or projections 3 and 4 received in the slots or recesses 6 and 7. Jewels or other articles deposited for safe keeping will be positioned within the pocket formed by the recesses 10 and 11 and when it is desired to remove the jewels or other articles the box or receptacle will be inverted to the position shown in Fig. 3 of the drawing and this movement will cause the locking pin 14 to drop into the recess 12 which is of sufficient depth to receive the entire pin. When thus positioned the normal top section 2 may be slid longitudinally

into the position shown in Fig. 3 to bring the recess 13 into alignment with the recess 9. When this is done the locking pin 15 will drop into the recess 13 and as the recess 13 is not of sufficient depth to receive the entire pin a portion of the pin will project into the recess 9, as shown in Fig. 3, and prevent further longitudinal movement of the section 2 relative to the section 1. This initial sliding movement of the section 2 relative to the section 1 does not entirely release the pin or projection 3 from the recess 6 and this prevents swinging movement of the section 2 relative to the section 1. To further release the section 2 the box or receptacle is again turned into its original position and this movement allows the locking pin 15 to again drop into the recess 9 so that the section 2 may be further slid longitudinally relative to the section 1 until the inner end of the slot or recess 7 engages the stud or projection 4. During this sliding movement of the section 2 relative to the section 1 the locking pin 14 will be held in the recess 12 due to the fact that the outer end of the pin rides over the upper surface of the bottom section 1. After the section 2 has been slid to the position just described it may be swung relative to the section 1, to the position shown in Fig. 5, and the jewels or other articles may be removed from the pocket or more particularly the recess 10. To relock the box or receptacle the movements are reversed.

From the above it will be seen that I have provided a novel form of box or receptacle for safely storing jewels or the like, a box or receptacle which does not have any key locking mechanism and a box or receptacle which may be readily locked or unlocked by manipulation of the parts in a manner known only to the person or persons entitled to gain access thereto.

Having fully described my invention what I claim as new and desire to secure by Letters Patent is:—

1. A receptacle of the character described including top and bottom sections, means normally positioned to lock the sections against movement one relative to the other, said locking means being released by inverting the receptacle to permit initial longitudinal movement of one section relative to the other, and means for locking the sections in said initially moved position, said last mentioned locking means being released upon returning the receptacle to its normal position to permit further longitudinal movement of one section relative to the other.

2. A receptacle of the character described including top and bottom sections, means normally positioned to lock the sections against movement one relative to the other, said locking means being released by inverting the receptacle to permit initial longitudinal movement of one section relative to the other, and means for locking the sections in said initially moved position, said last mentioned locking means being released upon returning the receptacle to its normal position to permit further longitudinal and swinging movement of one section relative to the other.

3. A receptacle of the character described including a bottom section having longitudinally spaced recesses in its inner face, a top section having longitudinally spaced recesses in its inner face, one recess of the bottom section being normally in alignment with one recess of the top section while the other recess of the bottom section is out of alignment with the other recess of the top section, a locking pin normally positioned in the aligned recesses for preventing longitudinal

movement of the sections one relative to the other, and a locking pin normally received in the other recess of the bottom section, said first mentioned locking pin being adapted for movement when the receptacle is inverted to permit an initial longitudinal movement of the sections, one relative to the other, to bring the recesses in the top and bottom sections, which are normally out of alignment into alignment, to permit the locking pin normally received in the recess of the bottom section to drop into the aligned recess of the top section and intersect the meeting faces of the sections to prevent further longitudinal movement of the sections one relative to the other, said last mentioned locking pin being released to permit further movement of the sections one relative to the other when the receptacle is returned to its normal position.

4. A receptacle of the character described including a bottom section having longitudinally spaced recesses in its inner face, a top section having longitudinally spaced recesses in its inner face, one recess of the bottom section being normally in alignment with one recess of the top section while the other recess of the bottom section is out of alignment with the other recess of the top section, a locking pin normally positioned in the aligned recesses for preventing longitudinal movement of the sections one relative to the other, a locking pin normally received in the other recess of the bottom section, said first mentioned locking pin being adapted for movement when the receptacle is inverted to permit an initial longitudinal movement of the sections, one relative to the other, to bring the recesses in the top and bottom sections, which are normally out of alignment into alignment, to permit the locking pin normally received in the recess of the bottom section to drop into the aligned recess of the top section and intersect the meeting faces of the sections to prevent further longitudinal movement of the sections one relative to the other, said last mentioned locking pin being released to permit further movement of the sections one relative to the other when the receptacle is returned to its normal position.

5. A receptacle of the character described including top and bottom sections, one of said sections having recesses extending inwardly from opposite ends thereof, projections carried by the other section and operable in the recesses, said projections being formed and adapted to prevent facewise separation of the sections but permitting longitudinal movement of one section relative to the other, and means for normally holding the sections against longitudinal movement, said means being released by turning the receptacle upside down.

6. A receptacle of the character described including top and bottom sections, one of said sections having recesses extending inwardly from opposite ends thereof, projections carried by the other section and operable in the recesses, said projections being formed and adapted to prevent facewise separation of the sections but permitting longitudinal movement of one section relative to the other, means for normally holding the sections against longitudinal movement, said means being released by reversing the position of the receptacle to permit initial longitudinal movement of one section relative to the other while maintaining the projections of the one section

- in the recesses of the other section, and means for locking the sections in said initially moved position, said last mentioned locking means being released upon returning the receptacle to 5 its normal position to permit further longitudinal movement of one section relative to the other and moving one of the projections entirely from its recess to permit swinging movement of the one section relative to the other.
- 10 7. A receptacle of the character described formed of sections adapted for movement of one relative to the other, and a pair of members one of which is normally positioned to lock the sections against relative movement but adapted to 15 be released by turning the receptacle upside down to permit an initial longitudinal movement of one section relative to the other, the other member occupying a position to arrest said initial movement, and said last mentioned member being released to permit a further longitudinal movement of the one section relative to the other by returning the receptacle to its normal position.
- 10 8. A receptacle of the character described formed of sections adapted for movement of one relative to the other, and a pair of members one of which is normally positioned to lock the sections against relative movement but adapted to 20 be released by turning the receptacle upside down to permit an initial longitudinal movement of one section relative to the other, the other member occupying a position to arrest said initial movement, and said last mentioned member being released to permit a further longitudinal and swinging movement of the one section relative to the other by returning the receptacle to 25 its normal position.
- 10 9. A receptacle of the character described formed of sections adapted for movement of one relative to the other, and a pair of pins cooperating with recesses in the sections for locking the sections against relative movement, one of the pins being normally positioned in aligned 30 recesses in the sections to intersect the meeting faces of the sections while the other pin is normally received in a recess of one section out of alignment with a recess in the other section, the first mentioned pin being positioned so as not to intersect the meeting faces of the sections by turning the receptacle upside down and permitting an initial longitudinal movement of one section relative to the other, said movement being limited by the second mentioned pin entering the 35 recess normally out of alignment therewith to intersect the meeting faces of the sections, and the second mentioned pin being returned to its initial position by turning the receptacle to its original position and permitting further longitudinal movement of the one section relative to the other.
- 10 10. A receptacle of the character described formed of sections adapted for movement of one relative to the other, and a pair of pins cooperating with recesses in the sections for locking the sections against relative movement, one of the pins being normally positioned in aligned 40 recesses in the sections to intersect the meeting faces of the sections while the other pin is normally received in a recess of one section out of alignment with a recess in the other section, the first mentioned pin being positioned so as not to intersect the meeting faces of the sections by turning the receptacle upside down and permitting an initial longitudinal movement of one section relative to the other, said movement being limited by the second mentioned pin entering the recess normally out of alignment therewith to intersect the meeting faces of the sections, and the second mentioned pin being returned to its initial position by turning the receptacle to its original position and permitting further longitudinal and swinging movement of the one section relative to the other.
